2,233,750

REFRIGERATOR

Tage Schullström, Stockholm, Sweden, assignor,
by mesne assignments, to Servel, Inc., New
York, N. Y., a corporation of Delaware

Application July 10, 1940, Serial No. 344,622
In Germany July 3, 1939

7 Claims. (Cl. 62—1)

My invention relates to refrigerators, and more particularly to a movable burner for use in refrigerators operated by heat.

It is an object of the invention to provide an improvement for moving into and out of its normal operating position a liquid fuel burner which may be mounted on a fuel tank and movable therewith.

In employing a burner of the character described above, it is desirable that the chimney of the burner will always accurately align itself with the flue associated with the heat receiving part of the refrigerator. With such proper alignment of the parts, the flame produced by the burner will always be accurately centered with respect to the flue, and admission of air at the juncture of the burner and the flue is prevented. Since the burner from time to time is removed from its normal operating position and subsequently moved back to such position, it is desirable to effect readily the proper alignment of the burner chimney and the flue.

The above and other objects and advantages of the invention will be apparent from the following description and accompanying drawings forming a part of this specification, and of which:

Fig. 1 is a fragmentary view, partly in section, of a refrigerator provided with apparatus embodying the invention in which the burner is illustrated in one position that it assumes during movement toward and away from its normal operating position;

Fig. 2 is a view similar to Fig. 1 illustrating the burner in another position that it assumes prior to movement into its normal operating position or just after removal from such position;

Fig. 3 is a view similar to Figs. 1 and 2, illustrating the burner in its normal operating position;

Fig. 4 is a sectional view taken on line 4—4 of Fig. 3.

Fig. 5 is an enlarged fragmentary view taken on line 5—5 of Fig. 3; and

Fig. 6 is an enlarged fragmentary view taken on line 6—6 of Fig. 4.

Referring more particularly to Fig. 1, reference character 10 designates a refrigerator cabinet which encloses a heat insulated food storage space 11. The cabinet is supported some distance above the floor by means of legs 12. Suitably supported by the cabinet 10 is a generator 13 forming part of an absorption refrigerating apparatus of the type disclosed in United States Patent No. 1,837,767 to Elfving. This generator

includes an outer shell 14 through which extends a flue 15, the lower end of the flue extending beyond the lower end of the shell.

Suitably supported below the cabinet 10 by means of brackets 16 and 17 is a pair of parallel horizontal tracks 18. Each track consists of a U-shaped channel having an upper horizontal flange 19 and a lower horizontal flange 20 connected by a vertical web 21. The upper flange 19 terminates short of both ends of the channel, 10 and is preferably flared upwardly, as shown at 22 and 23 in Figs. 1 to 3 inclusive.

Reference character 24 designates a fuel tank to which is fixed a burner 25. This burner may be of a well known type having a wick 26 which 15 extends into the tank 24, as best shown in Fig. 5. Suitable mechanism for raising and lowering the wick is provided and may be operated by a rod 27 which is supported in a bracket 28 and provided with a knob 29. The burner includes a 20 chimney 30 which is preferably made of glass in order that the flame therein may be observed. A plate 31 is provided with an annular groove into which extends the upper circular edge of the chimney. This plate is provided with a central aperture 32 of slightly less diameter than the interior diameter of the chimney.

Rigidly secured to the tank in the neighborhood of the burner 25 is a hood-like member 33 having a substantially flat top or upper wall 34. 30 The front end of the hood member, that is, the part nearest the control knob 29, is preferably open in order that the flame within the chimney 30 may be viewed. The upper wall 34 is provided with an aperture 35 and a V-shaped guide member 36 is secured to the top side of this wall with the opening 35 within the apex of the V, as best shown in Fig. 4.

A bracket 37 is fixed to the lower end of the flue 15, as by welding, for example, and carries 40 a locating pin 38 which extends downwardly from the bracket, the lower end of this pin being tapered, as shown at 39 in Fig. 6.

The tank 24 is provided with pairs of rollers 40 and 41. The rollers 41 are located on each side of the tank at the end thereof adjacent to the burner 25, and the rollers 40 are located on each side of the tank near the center thereof and somewhat closer to the burner end of the tank than to the other end. In other words, the 50 rollers 40 are located between the burner end of the tank and the center of gravity thereof. The rollers 40 are placed lower than the rollers 41 so that, when the axes of the rollers 40 and 41 are in horizontal alignment, the tank 24 is tipped 55

and in an inclined position, as shown in Figs. 1 and 2. The diameter of the rollers is slightly less than the vertical distance between the flanges 19 and 20 of the tracks 18.

5 The tank 24 is provided with a filler spout 42 near its forward end adapted to be closed by a cap 43. The filling end of the tank is also provided with a handle 44 to facilitate removal and subsequent positioning of the tank.

10 The above described device operates as follows:

In order to place the tank and burner in their normal operating position, the rollers 41 are placed on the forward ends of the tracks 18.

15 This may be easily done inasmuch as the upper flange 19 is cut away and flared upwardly, as shown at 23 in Figs. 1 to 3. The tank is then pushed to the left, as viewed in Fig. 1, the burner end of the tank being supported by the rollers 41, until the rollers 40 reach the forward end of the track. Thereupon, rollers 40 engage the tracks and support the tank in the position shown in Fig. 1. The rollers 40 are located sufficiently nearer to the left hand or burner end 20 of the tank than to the right hand or filling end, so that the tank 24 always tends to rotate in a clockwise direction about the axes of the rollers 40. During rearward movement of the tank 24 and the burner 25, however, the rollers 41 contact the lower sides of the upper flanges 19 and 25 keep the tank 24 in the inclined position illustrated in Figs. 1 and 2.

In the position shown in Fig. 2, at which position the rollers 41 are just about to leave the upper flanges 19, it will be seen that the top of the chimney 30 is able to pass underneath the lower end of the flue 15. When the rollers 41 do leave the flanges 19, the locating pin 38 strikes the top or upper wall 34 of the hood member 33 to keep the tank 24 in its inclined position until the tank has been pushed in far enough for the locating pin 38 to enter the opening 35. The V-shaped member 36 guides the hood 33 and the tank 34 laterally to make certain that the pin 38 enters the opening 35. When this occurs the unbalanced weight of the tank causes it to pivot slightly in a clockwise direction about the axes of rollers 40 to the position shown in Fig. 3, at which position the lower end of the flue enters the depression formed in the plate 31 carried by the chimney 30. The pin 38 and the opening 35 are so positioned that, when the pin enters the opening, the chimney is properly aligned with the lower end of the flue.

55 Due to the fact that the pin 38 and opening 35 are located very close to the chimney and flue, any slight error in manufacture in not locating the pin and the opening in their exact position for proper alignment will not be magnified, as 60 would be the case if these locating members were positioned some distance from the junction of the burner chimney and the flue.

In order to remove the tank and burner, the handle 44 is grasped and pulled upwardly in order to cause the burner end of the tank 24 to move downwardly about the rollers 40, thus disengaging the pin 38 from the opening 35. This also disengages the chimney from the flue, so that the tank 24 may be pulled forward along the tracks 18.

It will be apparent that an improved apparatus has been provided for accurately locating the burner with respect to the flue at all times. While I have described one more or less specific embodiment of my invention, it is to be under-

stood that this has been done for the purpose of illustration only, and that the scope is not to be limited thereby, but is to be determined from the following claims.

What is claimed:

1. In a refrigerator including a heat receiving element having a flue, a removable fuel storage member, a burner mounted near one end of said member, means for supporting and guiding said member during insertion and removal so that 10 said burner passes beneath the lower end of said flue, and means for tilting said one end of the member upwardly when the burner is beneath the flue.

2. In a refrigerator including a heat receiving element having a flue, a removable fuel storage member, a burner having a chimney mounted adjacent to one end of said member, rails for supporting and guiding said member during insertion and removal so that the chimney of said 20 burner passes beneath the lower end of said flue, and means for tilting said one end of the member upwardly when the burner is beneath the flue so that said chimney forms a continuation 25 of said flue.

3. In a refrigerator including a heat receiving element having a flue, a removable member, a burner mounted near one end of said member, means for supporting said member in an inclined position during insertion and removal so that 30 said burner passes beneath the lower end of said flue, means for guiding said member laterally to align said burner with said flue, and means for tilting said one end of the member upwardly when the burner is so aligned. 35

4. In a refrigerator including a heat receiving element having a flue, a removable member, a burner having a chimney mounted adjacent to one end of said member, supporting means secured to said member adjacent to said one end 40 thereof, supporting means secured to said member between said one end and the center of gravity of said member, and substantially horizontal guide rails for engaging both of said supporting 45 means, the first mentioned supporting means being located higher up on said member than the second mentioned supporting means whereby said member is maintained in an inclined position when said supporting means engage said rails so that said burner may pass beneath said flue, said first mentioned supporting means being releasable from engagement with said rails when said burner is beneath the flue, whereby the unbalanced weight of said member tilts said end thereof upwardly to bring said 50 burner into contact with said flue. 55

5. In a refrigerator including a heat receiving element having a flue, a removable member, a burner having a chimney mounted adjacent to one end of said member, supporting means secured to said member adjacent to said one end thereof, supporting means secured to said member between said one end and the center of gravity of said member, and substantially horizontal 60 guide rails for engaging both of said supporting means, the first mentioned supporting means being located higher up on said member than the second mentioned supporting means whereby said member is maintained in an inclined position when said supporting means engage said 65 rails so that said burner may pass beneath said flue, said first mentioned supporting means being releasable from engagement with said rails when said burner is beneath the flue, and means for guiding said member laterally to align said 70 burner with said flue. 75

burner with said flue when the first mentioned supporting means are released, the unbalanced weight of said member causing it to tilt said one end thereof upwardly when the first mentioned 5 supporting means is released to thereby bring said burner into contact with said flue.

6. In a refrigerator including a heat receiving element having a flue, a removable fuel tank, a burner mounted near one end of said tank, a 10 pair of rollers on said tank adjacent to said one end and a pair of rollers between said one end and the center of gravity of said tank, a pair of substantially horizontal guide rails having upper and lower flanges, said rollers being receivable 15 between said flanges, the first mentioned pair of rollers being located higher on said tank than the other pair, whereby the tank is inclined when the rollers are between said flanges, the upper flanges terminating short of the ends of said 20 rails whereby the unbalanced weight of said tank causes the latter to tilt to bring said burner into contact with said flue after the first mentioned rollers pass beyond the ends of the upper flanges.

7. In a refrigerator including a heat receiving element having a flue, a removable fuel tank, a burner mounted near one end of said tank, a pair of rollers on said tank adjacent to said one end and a pair of rollers between said one end and the center of gravity of said tank, a pair of substantially horizontal guide rails having upper and lower flanges, said rollers being receivable 5 between said flanges, the first mentioned pair of rollers being located higher on said tank than the other pair, whereby the tank is inclined when the rollers are between said flanges, a locating pin in fixed relation with respect to said flue, a member fixed on said tank and having an aperture for receiving said pin, and a V-shaped guide 10 secured to said member with said aperture within the apex thereof, the upper flanges terminating short of the ends of said rails whereby the unbalanced weight of said tank causes the latter to tilt to bring said pin into contact with said member after the first mentioned rollers pass beyond the ends of the upper flanges, said V-shaped guide guiding said pin into said aperture. 15 20
